B. BERKMANN

SURGICAL INSTRUMENT

Filed Nov. 3, 1924

Inventor:
Boris Berkmann
By Cheever & Cox Atty.

UNITED STATES PATENT OFFICE.

BORIS BERKMANN, OF CHICAGO, ILLINOIS.

SURGICAL INSTRUMENT.

Application filed November 3, 1924. Serial No. 747,466.

To all whom it may concern:

Be it known that I, BORIS BERKMANN, a citizen of the Republic of Poland, having declared my intention of becoming a citizen 5 of the United States, residing at Chicago, in the county of Cook and State of Illinois, have invented a certain new and useful Improvement in Surgical Instruments, of which the following is a specification.

10 My invention relates to multiple needle holders for surgical use, and the object of the invention is to provide improved means for attaching and detaching the needles to the holder.

15 I obtain this object by the mechanism illustrated in the accompanying drawing in which—

Figure 1 is a perspective view of my holder showing the same in use.

20 Figure 2 is a side elevation of the complete device.

Figure 3 is a view of the back of the locking bar showing some of the needle shanks in cross section.

25 Figure 4 is a view similar to Figure 2 but showing the holder bar and locking bar partially in cross section.

Figure 5 is a sectional view on the line 5—5 Figure 4.

30 Figure 6 is a perspective view of a modified form of needle in which the eye instead of being a mere perforation has an opening at the side of the needle.

Like numerals denote like parts throughout the several views.

35 In the form selected to illustrate the invention the device has a holder bar 10 provided with a handle 12, which by preference extends obliquely from one end of the bar so that the patient's body will not interfere with the hand of the user.

40 The bar has a plurality of T slot apertures having narrowed portions 14 spaced along it at regular intervals, in the present case there being four. On the back of the holder bar a locking bar 16 is slidably mounted. It has longitudinal slots 18 which cooperate with guide pins 20 projecting

from the back of the holder bar as best shown in Figure 4. The locking bar is also 50 provided with a set screw 22 which serves the double purpose of affording a handle by which the locking bar may be slid lengthwise and also means by which the locking bar may be secured in locking position. 55

The needles 24 have eyes 26 near their points. By preference the needles are curved in the usual manner. At their shanks they have shoulders 28 designed to abut the front of the holder bar 10. The shank portion of the needles, beyond the shoulders 28, have lateral slots 30 which form heads 32 projecting behind the locking bar as best illustrated in Figures 4 and 5. The locking bar has a T slot 14 for each needle and this produces an interlocking engagement between the locking bar and the shank of the needle. In other words, there is an interlocking engagement between the needle shanks and the two bars, and the needles may be firmly attached by first inserting the shanks through the apertures in the bar and then sliding the locking bar to locking position. The needles may, of course, be released by reversing the operation. 70 75

Having thus described my invention what I claim as new and desire to secure by Letters Patent is:

80 A surgical instrument of the class described having a needle having a shoulder near the end, a head at the end, and a slot between the shoulder and the head, a locking bar having an aperture for receiving the head portion of the needle beyond the shoulder, the shoulder being adapted to abut the front of the holder bar, and a locking bar 85 slidably mounted upon the back of the holder bar and having a T slot, one portion of which is large enough to pass the head of the needle, and the other portion of which is narrowed for engaging the head of the needle to prevent it from being withdrawn from the holder bar. 90

45 In witness whereof, I have hereunto subscribed my name.

BORIS BERKMANN.
